UNITED STATES PATENT OFFICE.

DAVID JAMES WINN, OF SUMTER, SOUTH CAROLINA.

BALE-TIE.

1,095,482.

Specification of Letters Patent.

Patented May 5, 1914.

Application filed May 24, 1913. Serial No. 769,637.

To all whom it may concern:

Be it known that I, DAVID JAMES WINN, a citizen of the United States, residing at Sumter, in the county of Sumter and State 5 of South Carolina, have invented certain new and useful Improvements in Bale-Ties, of which the following is a specification.

There are many reasons why a bale tie made of wire is a desirable one to use, especially in baling cotton. With the present style of bale tie having flat bands they required to be painted to prevent rusting and generally a coal tar paint is used which allows the cotton to stick to the tie. This cotton is hard to get off and causes a considerable loss in a large mill and the bands, being of flat iron, get bent and twisted and are hard to straighten and put in condition to use again. Again, the buckles being loose a 15 good many drop off and get into the cotton when the bales are opened at the mill and sometimes get into the machinery and start a fire.

My invention consists in the novel construction and arrangement of the parts 25 ordinary galvanized wire is used for the bands, and the buckles are formed of like cross section of material and remain permanently connected to one end of the wire and are of cheap and inexpensive construction, 30 easy to apply and easy to remove, and at the same time allowing the re-use of the wire.

My invention consists in the novel construction and arrangement of the parts which I will now proceed to describe with 35 reference to the drawing, in which:

Figure 1 is a top plan view. Fig. 2 is a longitudinal section, showing the bale tie applied to a bale. Fig. 3 is a view similar to Fig. 2, but showing the position of parts 40 in locking and unlocking the tie, and Fig. 4 is a sectional view, showing a simplified modification of the buckle.

In the drawings, B and B² represent the opposite ends of a galvanized wire tie.

C is a closed or continuous circular ring 45 of uniform cross section and of smooth round material.

A is a tongue of somewhat greater length than the diameter of the ring. This tongue 50 is permanently connected to one side of the ring by being bent around the same and the other end lies on top of and projects beyond the other side of the ring. The longitudinal axis of the tongue lies entirely above and to one side of the plane of the ring. In connecting the tongue to the ring its end a is bent

under and around the cross section of the ring and then up to the body of the tongue at a point about midway the length of the tongue, and terminates below the tongue and 60 in abutting contact therewith, so as to produce an elongated loop s which permits the tongue to slide back and forth longitudinally with a slip connection and to have a pivotal connection with the ring and also to 65 slide loosely around the ring to any diametrical position thereon.

In applying the bale tie, one end of the bale wire B² is looped around one side of the ring and its connection is made secure 70 by twisting. The tongue A of the buckle is then slid back over the ring by reason of the loop s until the end e is off the other side of the ring, as in Fig. 3. The other end B of the bale wire is then bent to form a loop b 75 which is inserted under the ring and pushed up through the same until the end e of the tongue can be entered through the loop and then the tongue A is moved bodily and longitudinally forward until the end e is 80 caught over the ring C, as in Fig. 2, in which position it is retained by the tension of the bale wire when the compression of the bale D is relaxed. When the bale tie is to be 85 removed from the bale, the tongue A is forced back until the end e is off of the ring and then the loop b of the wire band escapes therefrom, as seen in Fig. 3.

In constructing the ring C I prefer to make it circular, so that the tongue A may 90 slide around to any diametrical position on the same and thus prevent the weakening of the ring by concentration of wear at one point, but the ring C may be made oval like a link, if desired.

With the form of buckle as described, the wire band does not need to be cut, but can be removed intact from the bale and used again.

As a modification, or, rather, simplification, of my invention, the tongue may be pivotally connected to the ring by being wrapped at one end around it to form a close fitting eye a', as seen in Fig. 4. This tongue has no longitudinal movement, but 100 in applying the wire the tongue A' is swung up as in dotted lines and the loop b' of the wire is raised up a little higher to be swung over it. In this case the release of the bale wire is effected by cutting the wire at a pre- 105 determined distance from the buckle so as to leave all the old wires of uniform length.

In pointing out the distinguishing features of my invention, I would call attention to the plain, smooth, circular ring C of continuous curvature and uniform cross section which permits the tongue to occupy varying diametrical positions on the ring, which not only distributes wear, but allows the angular position of the tongue to be changed in case the ring becomes elongated under tension, also the fact that the tongue is a single loose radially swinging bar made in one piece, and further that the end *a* of the elongated loop is carried up to abutting contact with the under side of the tongue near the middle, where it terminates and forms a brace or support for the tongue to resist any downward bending of the tongue under the great strain of the tension of the bale wire.

20 I claim:

1. A bale tie consisting of a ring of continuous curvature and uniform unobstructed cross section, a single radially swinging tongue loosely connected to one side of the ring by having its end bent around the same and capable of sliding entirely around the ring and having its free end extending across the other side of the ring.

2. A bale tie consisting of a ring of continuous curvature and uniform unobstructed cross section, a single radially swinging tongue loosely connected to one side of the ring by having its end bent around the same in the form of an elongated loop with its end carried up to abutting contact with the under side of the tongue near the middle

and terminating thereagainst and having its free end extending across the other side of the ring.

3. A bale tie consisting of a ring of continuous curvature and uniform unobstructed cross section, a single radially swinging tongue loosely connected to one side of the ring by having its end bent around the same and having its free end extending across the other side of the ring, in combination with a bale wire having one end looped around one side of the ring and the other end formed into a loop and extended under the ring and over the free end of the tongue. 40 45 50

4. A bale tie consisting of a ring of continuous curvature and uniform unobstructed cross section, a single radially swinging tongue loosely connected to one side of the ring by having its end bent around the same 55 in the form of an elongated loop with its end carried up to abutting contact with the under side of the tongue near the middle and terminating thereagainst and having its free end extending across the other side of the ring, in combination with a bale wire having one end looped around one side of the ring and the other end formed into a loop and extended under the ring and over the free end of the tongue. 60 65

In testimony whereof I affix my signature in presence of two witnesses.

DAVID JAMES WINN.
